IMPERVIOUS SHEET MATERIAL

George Arlington Moore, Louisville, Ky., assignor to Humoco Corporation, Louisville, Ky., a corporation of Delaware

Application October 26, 1937, Serial No. 171,001

8 Claims. (Cl. 91—68)

This invention relates to coated sheet material and to a method of making the same, and more particularly to a method of applying a stratified film to a sheet material such as paper or the like.

5 An object of the invention is to provide a novel coating for sheet material having pliable, moisture-proof, and adhesive characteristics.

Another object is to provide a novel coating 10 for sheet material comprising a film of a waxy and thermoplastic nature.

Another object is to provide a novel material 15 of the above type which is suitable for use as a blank in the making of containers for tobacco or the like.

Another object is to provide a novel material of the above type having a coating comprising a thermoplastic adhesive possessing properties suitable for effecting a moisture-proof seam.

20 Another object is to provide a novel material of the above type having a coating which is moisture-proof and impervious and which presents two primed, thermoplastic, adhesive surfaces.

Another object is to provide a fibrous sheet 25 material coated with a novel stratified film consisting of a layer of waxy material interposed between layers of thermoplastic cellulosic lacquer, said film having a brilliant surface gloss.

Another object is to provide a novel and improved continuous process or method for applying a stratified film of the above type to a web of sheet material.

30 A still further object is to provide a transparent, stratified film on sheet material, it being understood that the said material may be printed prior to the application of the film to the printed surface.

The above and further objects and novel features of the invention will more fully appear from 40 the following detailed description when read in connection with the accompanying drawing.

It is to be expressly understood, however, that the drawing is for the purpose of illustration only and is not intended as a definition of the 45 limits of the invention, reference being had primarily for this latter purpose to the appended claims.

In the drawing, wherein like reference characters refer to like parts throughout the several 50 views,

Fig. 1 is a diagrammatic view illustrating one method of coating a sheet material according to the present invention; and

55 Fig. 2 is an enlarged detail view illustrating

a seam or joint embodying the present invention.

In the embodiment shown, for purposes of illustration, the invention has been applied to a strip of sheet material, such as paper, which is 5 suitable for making small containers of the type used for tobacco or the like. It is to be understood, however, that the method may also be used for applying a coating to other types of material, such as Cellophane or other cellulosic material, 10 and is adapted, in any event, to produce a moisture-proof, thermoplastic coating thereon.

The invention provides for casting a layer or film of wax between two layers or films of a thermoplastic lacquer such as a nitro-cellulose lacquer, 15 to form a stratified coating having thermoplastic, adhesive properties imparted by the lacquer and having the moisture-proof properties of the wax. The first layer of lacquer serves to size the paper and to prevent the wax from being 20 absorbed thereby. It also supports the wax and is strongly adherent to the paper. The wax can be cast in an extremely thin layer as it is supported on the impervious lacquer base. The outer layer of lacquer protects the layer of wax and 25 facilitates the making of a joint or seam which may be adhesively secured by the use of heat and pressure, as will be more fully described.

In a coating of this type, a careful balance 30 should be maintained between the wax and lacquer because an excess of wax will tend to dissolve the solids from the lacquer and destroy the thermoplastic adhesive properties thereof, whereas a deficiency of wax will decrease the 35 imperviousness of the layers to moisture. It has been found that a thin layer of wax between two thin films of nitro-cellulose lacquer possesses the desired properties and provides a stock that is suitable for making moisture-proof tobacco containers and the like.

40 Referring to Fig. 1, the invention as shown, by way of example, is carried out by passing the strip material 9, such as paper, Cellophane or the like, from a reel 10, over an idler roll 11 and feed rolls 12, to a first coating station A. In the 45 embodiment shown, this coating station comprises a roll 14 registering with a reverse coating roll 15. The latter engages a transfer roll 16 which, in turn, receives a coating of lacquer of the type to be described from a roll 17 rotating 50 in a reservoir 18 which is fed through an inlet 19 with the lacquer or other material to be applied to the strip 9. The rolls 16 and 17 rotate in the bottom of the reservoir 18 in such a way that a coating of lacquer is picked up from the 55

reservoir by the roll 17 and is transferred therefrom to the roll 16 and thence to the roll 15 and to the upper surface of the strip 9. It will be noted that the roll 15 rotates in the reverse direction with respect to the direction of feed of the strip 9 so as to cause the film to be positively removed from the surface of the roll 15 and to be pressed or worked into the surface of the strip. A doctor blade 20 may be mounted in the reservoir 18 to control the film on the roll 16 so as to apply the desired thickness of film.

Various types of coating material and lacquers have been found suitable, preferably celluloses, such as Du Pont Lacquers Nos. 606, 543, 208, 15 or the like. These materials are thermoplastic in that they become activated when heated and, in addition to forming a coating over the surface of the web material, have sufficient adhesive properties so that the blanks cut from said material may be readily secured in shape by overlapped seams.

Although a particular type of coating mechanism has been described, it is to be understood that any standard type of mechanism may be 25 used for applying a continuous thin film of the lacquer to the strip 9 as it passes the station A.

The strip 9 with the coating 21 (Fig. 2) applied thereto is now passed through a suitable drying tunnel 22 (Fig. 1) for thoroughly drying the 30 lacquer film and is thence passed, at a wax station B, over a wax roll 25 which rotates with a fountain roll 26. The latter roll is located in a bath of wax 27 contained in a reservoir 28 which is heated by suitable means, such as electrical heating elements 29 shown in the base of the reservoir. The roll 25 may also contain an electrical 35 heating unit 30 if desired. It is to be understood that the reservoir 28 is maintained at the temperature required to maintain the wax in a molten condition and to apply the same to the strip 9 as a thin film 32 (Fig. 2) over the surface of the film 21. Various types of waxes may be used for this purpose, such, for example, as a paraffin wax, opal wax, or a resinous series of 40 hot melts, all referred to hereafter as wax. In any event, the wax is adapted to provide a thin, flexible, impervious coating which adheres to and is deposited on the film 21 of thermoplastic lacquer.

50 After passing the station B, the strip 9 passes around an idler roll 35 (Fig. 1) and thence to a station C at which a further coating of thermoplastic lacquer is applied. The web may be cooled by circulating air over the film to harden 55 the wax before it reaches the idler roll 35.

The station C may comprise rolls 14a, 15a, 16a and 17a cooperating with a reservoir 18a similar to the elements 14 to 18 described at station A. The reservoir 18a may be supplied with lacquer 60 through an inlet 19a and the roll 16a may be provided with a doctor blade 20a, as above described. In this station, a coating 36 (Fig. 2) of lacquer, similar to the coating 21, is applied over the surface of the wax film 32. This lacquer may 65 be of the same type as that applied at station A. In certain instances, however, it may be desirable to use one specific lacquer at station A and another specific lacquer at station C, depending upon the desired characteristics of the finished 70 film.

After passing station C, the strip 9 passes through a drying tunnel 38 which may be of considerable length and is preferably maintained at a temperature sufficiently low so as not to soften or 75 destroy the wax film. The tunnel 38 may be sub-

stantially longer than the tunnel 22 because of the lower temperature maintained therein and the consequent longer time required for drying the film. The strip then passes over an idler roll 39 and a set of feed rolls 40 which are similar to the feed rolls 12 above mentioned and may be geared together therewith so as to cause the strip to move at a uniform rate. The strip then passes over an idler roll 41 and may be rewound onto a reel 42.

It will be noted that the film 21 of lacquer, which is deposited on the strip 9, serves the purpose of priming the paper surface so that the wax is prevented from permeating the same. It also possesses thermoplastic properties and is actuated by heat and pressure for effecting a joint in the manner to be described.

The provision of a thin film of wax between two films of thermoplastic lacquer forms a plastic, pliable coating in which the lacquer protects the 20 wax and imparts thermoplastic adhesive properties to the coating while the wax forms a moisture-proof, impervious layer. The wax film is so thin in relation to the lacquer that the lacquer solids are prevented from being diluted by the 25 presence of the wax and destroying the effectiveness of the lacquer. The use of a lacquer film on each side of the wax film further reduces the tendency of the solids of the lacquer to enter into the wax and thereby reduce the effectiveness 30 thereof.

The above-described material is particularly suitable for forming blanks from which containers may be made and provides an effective means for making a moisture-proof, strongly adherent 35 seam. The method of making such a seam at the overlapped ends of the blank is illustrated in Fig. 2. It will be noted that the blank has been folded in such a way that the two outer thermoplastic layers 36 are in contact. Suitable heat 40 and pressure is then applied, as, for example, by a heated die 43, to activate the lacquer and at the same time to cause the wax to melt and permeate or mix with the lacquer. The film is also pressed to some extent into the fibrous material, 45 thereby impregnating the seam with moisture-repellent material.

It will be noted that the above-described invention provides an impervious, adhesive and flexible coating for a paper strip or the like which 50 has a wide field of usefulness and is especially suitable for use in making hermetically sealed containers of the type used in packaging tobacco and other similar articles having a definite moisture content which must be maintained therein 55 for a substantial period of time. The film has the combined properties of the wax and thermoplastic adhesive and is so formed that the wax does not prevent a firm adhesion at the overlapped seam. The process may be easily and 60 efficiently carried out and the stratified film provides a dependable means for moisture-proofing the entire container and for effecting an adhesively secured seam. The process is continuous, thus reducing handling time and expense, and 65 avoiding damage to and imperfections in any one layer of the film. The outer surface of the film has a brilliant gloss which greatly enhances the eye appeal and salability of an article embodying the same. If desired, the film may be colored or 70 transparent, and, if transparent, is readily applied over printed matter.

Although a particular embodiment of the invention has been illustrated and described, it is to be expressly understood that the same is not 75

limited thereto, but that various changes may be made therein without departing from the spirit and scope of the invention as will now be understood by those skilled in the art. For a definition 5 of the limits of the invention, reference is had primarily to the appended claims.

What is claimed is:

1. The method of coating a fibrous material which comprises applying a film of nitro-cellulose lacquer to the surface thereof, drying said film, casting a wax film thereon, hardening the latter, casting a second film of nitro-cellulose lacquer on said wax film, and drying said second film.
- 10 2. The method of applying thermoplastic, moisture-proof film to a strip of fibrous material which comprises passing said strip continuously past a plurality of coating stations, applying a film of cellulose lacquer at a first station, passing 20 the strip through a drying zone between the first and second stations, applying at the second station a layer of wax over said first layer, causing the wax to harden, applying at the third station a layer of cellulose lacquer over said wax, and 25 passing the film through a second drying zone in which the last film is caused to set, said second drying zone being maintained at a temperature sufficiently low to prevent undue softening of the wax.
- 30 3. A fibrous sheet material having a surface coated with a stratified film comprising a layer of lacquer in contact with said surface, a layer of wax formed on said first layer and a second layer of lacquer deposited over said layer of wax.
- 35 4. A fibrous sheet material having a surface coated with a stratified film comprising a layer of cellulose lacquer in contact with said surface, a layer of wax formed on said first layer and a second layer of cellulose lacquer deposited over 40 said layer of wax.

5. A fibrous sheet material having thereon a stratified coating comprising a layer of wax interposed between two layers of cellulose lacquer, said layer of wax being sufficiently thin with respect to the lacquer layers to prevent the adhesive properties of the lacquer from being materially affected by solution of the solids thereof into the wax.

6. The method of applying a thermoplastic moisture-proof coating to fibrous material which 10 includes applying a thin film of thermoplastic lacquer to the surface of said material, drying said film, applying a thin layer of wax to the surface of said film, hardening said layer, applying a film of thermoplastic lacquer to the surface of said layer, and immediately drying said 15 last-named film.

7. The method of coating fibrous material which includes applying a thin film of liquid lacquer to the surface of the material, passing 20 the latter through a dryer to dry said film, applying a thin layer of wax to the surface of said dry film, hardening said layer of wax, applying a film of liquid lacquer to the surface of said layer, and immediately drying said second-named film 25 at a temperature above the melting point of said wax layer.

8. The method of coating fibrous material which comprises applying a film of liquid lacquer to the surface of said material, subjecting said 30 material to heat for drying said lacquer film, applying a thin layer of wax to the surface of said film, passing said material through a cooling zone for hardening said wax layer, applying a thin film of liquid lacquer to the surface of 35 said wax layer, and immediately subjecting the material to heat at a temperature sufficiently low to prevent undue softening of the wax for drying said second film of lacquer.

GEORGE ARLINGTON MOORE. 40
